UNITED STATES PATENT OFFICE.

SUSIE DERRY PARKER, OF MACON, GEORGIA.

DESIGN FOR A BADGE.

No. 38,048.

Specification for Design.

Patented June 5, 1906.

Application filed March 5, 1906. Serial No. 304,413. Term of patent 14 years.

To all whom it may concern:

Be it known that I, SUSIE DERRY PARKER, a citizen of the United States, residing at Macon, in the county of Bibb and State of Georgia, have invented a new, original, and ornamental Design for a Badge, of which the following is a specification, reference being had to the accompanying drawing, forming a part thereof.

The figure is a plan view of a badge, showing my new design.

I claim—

The ornamental design for a badge, as shown.

SUSIE DERRY PARKER.
